UNITED STATES PATENT OFFICE

105,088

DESIGN FOR AN ACCORDION

Emilio Catena, New York, N. Y.

Application May 8, 1937, Serial No. 69,231

Term of patent 7 years

To all whom it may concern:

Be it known that I, Emilio Catena, a citizen of the United States of America, residing at New York city, Bronx County, State of New York, have invented a new, original, and ornamental Design for an Accordion, of which the following is a specification, reference being had to the accompanying drawing, forming a part hereof, wherein— Fig. 1 is a front view of an accordion showing my new design;

Fig. 2 is a top plan view thereof; and

Fig. 3 is an end view of same.

I claim:

The ornamental design for an accordion, substantially as shown.

EMILIO CATENA.
